Jas. C. Hobensmith

ATTORNEY

UNITED STATES PATENT OFFICE.

HELEN GERITS, OF PHILADELPHIA, PENNSYLVANIA.

HOOK MEMBER OF HOOK-AND-EYE FASTENER.

1,282,066.

Specification of Letters Patent.

Patented Oct. 22, 1918.

Application filed October 23, 1917. Serial No. 198,042.

To all whom it may concern:

Be it known that I, HELEN GERITS, a citizen of the United States, residing at Philadelphia, in the county of Philadelphia and State of Pennsylvania, have invented certain new and useful Improvements in Hook Members of Hook-and-Eye Fasteners, of which the following is a specification.

My invention relates to a hook member 10 of a hook and eye fastener and it has particular relation to such a hook member which is preferably made from a single piece of bent wire of a novel conformation, as will be hereinafter more particularly set 15 forth.

The principal object of my invention is to provide an improved form of hook member of a hook and eye fastener which will be simple in construction, durable and efficient 20 in use, and which will be susceptible of being easily attached to the garment with a minimum of stitching, but which will be maintained properly on the garment notwithstanding the more or less rough usage to 25 which such devices are subjected when in use, and which on account of its peculiar conformation will resist deformation when undue stresses occur in use.

Heretofore, it has been usual in such devices to provide sewing loops at the rear end 30 of the shank thereof, and in the most commonly used form of hook member it has been customary for the user to also stitch the forward end of the hook member fast to the 35 garment by a few stitches across the forward end of the shank beneath the bill. When these devices were so fastened to the garment and the hook member was detached from the eye member with which it 40 was used, usually by being pushed forward from the rear, the stitches which were at the front end of the shank portion would ride along the shank and either become foul on the "hump" portion, or would be retained 45 near the rear end of the shank by said hump portion. This disarrangement would not only mar the appearance but would also result in the front end of the hook member being more or less free, tending to the ultimate 50 unfastening of the hook member from the stitching, or to the destruction thereof by the improper stresses to which the device would thus be subjected.

Various attempts have been made to overcome the difficulty above mentioned, such as

the provision of sewing loops at the forward end of the hook member, and other more or less clumsy expedients were tried which however were not found satisfactory in use.

The present invention contemplates a 60 novel form of construction whereby the stitching at the forward end of the hook member will at all times be maintained in the proper location with respect to the member, and which will also permit the fastening of the front end of the device to the garment with a minimum of stitching, and which will maintain its proper shape even when subjected to considerable stress. 65

The nature and characteristic features of 70 my invention will be more readily understood from the following description taken in connection with the accompanying drawings forming part hereof, in which—

Figure 1 is a top or plan view, enlarged, 75 of a hook member of a hook and eye fastener embodying the main features of my invention;

Fig. 2 is a side elevation thereof; and

Fig. 3 is a view of a portion of a garment 80 showing devices of my invention in operative position thereon.

Referring to the drawings, in the particular embodiment of my invention therein shown, the hook member is preferably made 85 from a single piece of wire bent and formed as therein shown, and comprising as essential elements, a shank portion 5, and a bill portion 6, and preferably a spring tongue 7 having a retaining hump 8. The bill portion 6, comprises two substantially parallel 90 portions of the wire which are each bent around as at 11 at the forward end of the hook member and there merged into the respective side portions 9 and 10 of the shank 95 5. One of these side portions 9 is first bent abruptly outward a short distance from the forward end to form an enlarged shoulder 14 and is then continued toward the rear end and bent inward as at 16 to a point adjacent the spring tongue 7, and the wire is then bent outward, extending to and merging into a substantially circular inturned 100 sewing loop 12 at the rear of the hook member. The other side portion 10 of the shank 105 5 is similarly bent outward a short distance from the forward end to form a shoulder 14 and is then continued toward the rear end and bent inward as at 17 to a point adjacent the spring tongue 7, and thence ex- 110

tends to a semicircular sewing loop 13, from which the centrally arranged spring tongue 7 extends forward beneath the bill portion 6. The spring tongue 7 is preferably provided with a hump 8 which serves to normally maintain the hook member in engagement with the eye member in the well known manner in which such hump devices operate.

All of the portions of the shank 5 are arranged in the same plane so as to present a smooth flat surface next to the garment to which the device is attached. It will be noted that the shoulders 14 in the shank 5 are formed a short distance from the front 15 end of the hook member where the portion of the wire from the bill portion 6 bends around into the side portions 9 and 10 of the shank, as clearly shown in Figs. 1 and 3 of the drawings, and these shoulders 14 serve 20 to maintain the stitching at the front end of the hook member at all times in proper relative position. This arrangement also results in the provision of a wide base near the forward end of the shank for the support of the hook member on the garment at this point. By bending the shank members inwardly as at 16 and 17 in proximity to the spring tongue 7, the hook member will be less likely 25 to be distorted in use on account of the support which will be afforded by the seat formed by the spring tongue 7 when undue stress occurs, and to facilitate this action the spring tongue 7 may be slightly depressed beneath the plane of the shank 5 as 30 shown in Fig. 2 of the drawings, it being noted that the bend between the depressed portion of the spring tongue 7 and the hump portion 8 will constitute a recess in which the inturned portions 16 and 17 of the shank 35 will seat when such stress occurs in use.

To attach the device to the garment the sewing loops 12 and 13 at the rear end thereof are stitched to the garment as clearly shown in Fig. 3 of the drawings, and the forward end of the hook member is also attached by a number of stitches 15 which extend across the end of the shank under the bill and in front of the shoulders 14, so that the hook will be securely fastened to the 45 garment at each end of the shank, and the shoulders 14 will as hereinbefore set forth effectively prevent the stitches 15 from sliding along the shank 5 when the hook is being manipulated by the user.

It will thus be seen that there is provided 55 a simple, durable, and efficient form of hook member which may be attached to the garment with a minimum of stitching, but which, when attached, will be more permanently and securely held than heretofore

has been done, and this without the provision of complicated and cumbersome parts.

Having thus described the nature and characteristic features of my invention, what I claim as new and desire to secure by Letters Patent is:

1. A hook member of a hook and eye fastener formed of bent wire and comprising a bill for engaging the eye and a shank for attachment to the garment, said bill 70 comprising parallel portions of the wire which extend substantially parallel to the plane of the shank and are bent around at the forward end and merge into the shank, the wire thence extending rearwardly a 75 short distance of substantially the same width as the bill, then diverging to form shoulders and extending into more widely disposed side portions of the shank, said side portions thence extending rearwardly 80 and having portions at the rear bent around to form sewing loops at the rear end of the shank, all of the parts of the shank lying in substantially the same plane, and a centrally disposed spring tongue extending forward from one of the sewing loops having an intermediate depressed portion and a hump portion near its forward end adapted to co-act with the bill as a retaining means 85 to restrain accidental disengagement from the eye.

2. A hook member of a hook and eye fastener formed of bent wire and comprising a bill for engaging the eye and a shank for attachment to the garment, said bill comprising parallel portions of the wire which extend substantially parallel to the plane of the shank and are bent around at the forward end and merge into the shank, the wire then extending rearwardly a short distance of substantially the same width as the bill, then diverging to form shoulders and extending into more widely disposed side portions of the shank, said side portions thence extending rearwardly and being bent 100 inward intermediate the ends, and said side portions having portions at the rear bent around to form sewing loops at the rear end of the shank, all of the parts of the shank lying in substantially the same plane, and a 105 centrally disposed spring tongue extending forward from one of the sewing loops having an intermediate depressed portion and a hump portion near its forward end adapted to co-act with the bill as a retaining 110 means to restrain accidental disengagement from the eye.

In testimony whereof I have hereunto signed my name.

HELEN GERITS.
